BRASSIÈRE

Molly Berns, New York, N. Y.

Application July 23, 1943, Serial No. 495,879

3 Claims. (Cl. 2—42)

This invention relates to women's apparel and more particularly to a novel improvement in brassières.

A primary object is to provide a garment of unique and extraordinary simplicity from the standpoint of manufacture, and, which in use, provides proper and adequate support for the breasts in a comfortable and practical way whether the garment is used for beach or sports-wear or as an ordinary undergarment. In that connection the invention fundamentally involves a piece of square or diamond shaped fabric folded to form two substantially triangular sections fitted with shoulder straps and body ties so that when the garment is positioned on the body, the erstwhile lower apices or free ends of the triangles may be lifted and tied together to provide a pair of cupped supports for both breasts.

A further object of the invention is to provide a brassière of standardized shape or pattern, which for example, in most cases, may be derived from handkerchiefs or scarfs of different size. That is to say, stock sizes of handkerchiefs or scarfs may be used as the basis for garments of different size, thereby to provide small, medium, and large garments to suit different profiles and bust sizes within the range usually recognized in the industry.

With the above and other objects in view which will more readily appear as the nature of the invention is better understood, the same consists in the novel combination and arrangement of parts hereinafter more fully described, illustrated and claimed.

A preferred and practical embodiment of the invention is shown in the accompanying drawings, in which:

Fig. 1 is a plan view of the base material before folding, constituting the brassière.

Fig. 2 is a front elevation of the material shown in Fig. 1 folded diagonally to produce two substantially triangular layers or sections of material (see Fig. 4).

Fig. 3 is a front elevation of the folded material of Fig. 2 provided with shoulder straps and body ties.

Fig. 3a is a front elevation, similar to Fig. 3, but showing a modification.

Fig. 4 is a vertical cross-section taken on the line 4—4 of Fig. 3.

Fig. 5 is a top plan view of the construction shown in Fig. 3.

Fig. 6 is a rear perspective view showing the garment as it would be applied to the body with the apices of the triangular sections separated to

better illustrate the beginning of the cup forming operation.

Fig. 7 is a perspective view, similar to Fig. 6, illustrating the second step in the formation of the cups, namely, the pulling upward of the apices referred to in connection with Fig. 6.

Fig. 8 is a perspective view, similar to Fig. 6, illustrating the last step of tying the apices of the folded sections into a knot to form the breast supporting cups.

Fig. 9 is a front perspective view of the garment as it appears in Fig. 8.

Fig. 10 is a vertical cross-section taken at the position of the knot in Fig. 9.

Fig. 11 is a diagrammatic view illustrating the use of a piece of base material of diamond shape form.

Similar reference characters designate corresponding parts throughout the several figures of the drawings.

As will be observed from the drawings, the piece of material from which the body of the brassière is made is designated generally as "A." In Fig. 1 this material is shown to be square. However,

as will be observed from Fig. 11 the original stock material may be of diamond shape formation, as indicated at A'. While it is preferred to utilize a single piece of material which is to be folded diagonally, nevertheless, it will of course be understood that it is within the purview of the invention to utilize a pair of triangular sections which may be sewed or stitched together to form a single piece of stock material.

Assuming that a square piece of material A is used, as shown in Fig. 1, the same is folded along the line B to provide front and rear triangular sections which, as will be apparent from Fig. 2, are brought into substantially registering relation, when folded.

With the material folded as shown in Fig. 2 and with the fold line uppermost so that the triangular tips or apices 1a and 2a are pointed downwardly, the folded material is provided with

suitable means for supporting it on the body. As will be apparent from Figs. 3 to 10 inclusive, the body of the brassière may be provided with the shoulder straps 3—3 which may be secured at one end, as indicated at 4, to the folded portion of the material inwardly of the lateral ends thereof but outwardly of the vertical center line of the registering triangular sections. The opposite ends 5 of the shoulder straps 3 are secured to the opposite corners of the triangular sections, as will be apparent from Figs. 3 and 5.

50
55

It will, of course, be understood that the shoulder straps 3 may be made of tape, ribbon, or elastic material, and although shown in the drawings as being of one piece, it will of course be understood that the said straps 3 may be made in two pieces so as to have the inner meeting ends tied into a bow knot.

The opposite corners of the triangular sections 1 and 2 are also provided with the body tie elements 6-16 which may be also made in one piece and of elastic material, if desired. In the embodiment shown the opposite corners 7 are shown as turned back upon themselves and stitched to provide a fastening ground for the ends 5 of the shoulder straps and the body ties 6. It may also be pointed out that it is within the scope of the invention to make the turned in corners 7 of the triangular sections in the form of a loop so that the ends 5 of the shoulder straps and the body tie 6 may be made in one piece and slide through the loop. In fact, any type of body supporting means well known in the art may be used to support the triangular registering sections 1 and 2 in position across both breasts.

After the garment is applied to the body with the aid of the shoulder straps 3 and body ties 6, as indicated in Fig. 6, the apices 1a and 2a of the sections 1 and 2 point downwardly and the wearer can then manipulate said apices so as to pull both of them upwardly above the fold line of the triangular sections, as shown in Fig. 7. The effect of thus positioning the apices 1a and 2a of the triangular sections is to bring a portion of the outer section 1 upwardly and also bring the inner portion of the inner portion upwardly. When the points or apices 1a and 2a are in the position shown in Fig. 7, they may be tied in a knot designated generally as "K" in Fig. 8. By thus tying the two sections together each of them will properly drape about each breast and form the desirable supporting cups illustrated in Figs. 8 and 9.

Fig. 3a illustrates a modification wherein the upper folded edge of the material outwardly of the points 4a where the straps are connected may be further folded on the bias as shown at E' to cause the upper edge of the garment to slope downwardly to each side of the body of the wearer, thus affording greater freedom of movement and greater shapeliness to the brassière itself. This is particularly true if the garment is of the custom made variety.

In Fig. 11 the diamond shaped piece of stock material will be folded to provide the registering sections 1b and 2b.

From the foregoing, it will be apparent that a distinctive feature of the invention resides in providing a piece of stock material which may

be folded so as to have its medial dimension greater than the opposite ends or corners, and, which, when supported on the body in a position to span both breasts, may be manipulated in the manner shown to provide the necessary cupped supports. It will of course be understood that any type of material may be used, such for example as handkerchief stock and the quality of the material will of course vary with the particular use to which the device is intended to be put.

I claim:

1. A brassière comprising a single piece of flexible sheet material folded upon itself along a straight line to provide free inner and outer superimposed layers, and means connected to said sheet at the ends of the fold line thereof for fastening it with its fold line disposed above the breasts and its inner and outer layers depending from its fold line and overlying the breasts, the said inner and outer layers being of substantially equilateral triangular shape with their bases comprised by the fold line whereby they are adapted to be turned inwardly and upwardly and outwardly and upwardly, respectively, and to be tied together above the fold line to provide breast accommodating and supporting pockets.

2. A brassière comprising a single piece of flexible sheet material of substantially rectangular shape folded upon itself along a straight diagonal line extending between opposite corners thereof to provide free inner and outer superimposed layers of substantially equilateral triangular shape with their bases comprised by the fold line, and means connected to said opposite corners of said sheet for fastening the sheet with its fold line disposed above the breasts and its inner and outer layers depending from said fold line and overlying the breasts to be turned inwardly and upwardly and outwardly and upwardly, respectively, and to be tied together above the fold line to provide breast accommodating and supporting pockets.

3. A brassière comprising a single piece of flexible sheet material folded upon itself along a straight line to provide free inner and outer superimposed layers, and means connected to said sheet at the ends of the fold line thereof for fastening it with its fold line disposed above the breasts and its inner and outer layers depending from its fold line and overlying the breasts, the said inner and outer layers being of greater depth medially than at their ends and being adapted to be turned inwardly and upwardly and outwardly and upwardly, respectively, and tied together above the fold line to provide breast accommodating and supporting pockets.

MOLLY BERN.
